UNITED STATES PATENT OFFICE.

CARL L. KOSTER AND FREDERICK J. DAVIS, OF SAN FRANCISCO, AND JULIUS J. KROHN,
OF ARCATA, CALIFORNIA.

RECORDING DEVICE.

1,187,068.

Specification of Letters Patent. Patented June 13, 1916.

Application filed June 8, 1915. Serial No. 32,839.

To all whom it may concern:

Be it known that we, CARL L. KOSTER, FREDERICK J. DAVIS, and JULIUS J. KROHN, citizens of the United States, the said CARL L. KOSTER and FREDERICK J. DAVIS residing in the city and county of San Francisco, State of California, and the said JULIUS J. KROHN at Arcata, county of Humboldt, State of California, have invented certain new and useful Improvements in Recording Devices, of which the following is a specification.

The present invention relates to an instrument primarily designed for use in logging camps or other places where cable hauling is employed, to record the travel of the cable on each trip thereof, the time required to make each trip, and to determine the efficiency of the crew operating with each cable.

The invention has for its principal objects to provide an apparatus whereby a record is made as to the distance traveled by the hauling cable during each trip thereof so that the life and record of the travel of the cable will be provided; to provide an apparatus which will record the interval of time required in making each trip of the cable, whereby an accurate record of the operation of any given crew working in connection with the cable may be had; one whereby the operator of the cable controlling means may readily ascertain at all times the length of cable unwound from the drum.

With the above mentioned and other objects in view, the invention consists in the novel construction and combination of parts hereinafter described, illustrated in the accompanying drawings and pointed out in the claims hereto appended; it being understood that various changes in the form, proportion, size, and minor details of construction within the scope of the appended claims may be resorted to without departing from the spirit or sacrificing any of the advantages of the invention.

To more fully comprehend the invention, reference is directed to the accompanying drawings, wherein—

Figure 1 is a diagrammatic view of a cable transporting system, such as used in logging camps, with an embodiment of the invention associated therewith. Fig. 2 is a front elevation, partly in section, of an embodiment of the invention, disclosing the

odometer, a portion of the means for operating the same, the marker coöperating with the face of the chart, and the time controlled instrument for operating the marker. Fig. 3 is a view in detail of the rotatably mounted chart supporting drum. Fig. 4 is a view in detail of the odometer operating mechanism. Fig. 5 is a transverse sectional view taken on line 5—5 of Fig. 2. Fig. 6 is a vertical sectional view taken on line 6—6 of Fig. 5, disclosing more fully the recording device and the mechanism for operating the same. Fig. 7 is a plan view of the indicating means on top of the cabinet and coöperating with the chart drum for designating the position of the end of the cable from the drum. Fig. 8 is a view in side elevation of the mechanism coöperating with the towing cable or back line and which operates the chart holding drum. Fig. 9 is a vertical sectional view taken on line 9—9, of Fig. 8, showing more fully the tension device for the grooved pulleys. Fig. 10 is a top plan view of the mechanism disclosed in Figs. 8 and 9 illustrating more fully the arrangement of the connecting links. Fig. 11 is a view in detail of the mechanism for resetting the recording device. Fig. 12 is a view in detail of the operating shafts taken on line 12—12 of Fig. 5.

While the device is disclosed as being operated by the back line cable, it is to be understood that the same may be equally as well applied to operate in connection with the towing or pulling cable, or, in fact, may be employed in connection with any cable or member which is extended for various lengths and relative to which a record of the travel thereof is desired to be obtained.

Referring more particularly to the several views of the drawings, wherein like characters of reference designate corresponding parts throughout the several views, 1 indicates a suitable main or towing cable of a logging equipment to one end of which is attached the back line 2 preferably of lighter material. The lines 1 and 2 operate around a suitable sheave 3 and are connected at their free ends to any suitable winding mechanism.

The back line 2 operates between the rotatable sheaves 4 and 5 respectively carried by shafts 6 and 7, supported by the stirrup 8, preferably suspended from a hanger 9, which provides a flexible support therefor.

The shaft 6 extends through vertical slots in the stirrup and through openings in a guide 10 slidably mounted in the stirrup 8, and the guide 10 is forced downwardly by the coiled spring 11 received at its opposite ends in cups 11' carried respectively by the stirrup and guide, and said spring is maintained under tension by the adjustable screw 12 passing through the top of the stirrup. 10 Suitable guide or steadyng rollers 13 between which the line 2 passes are connected by the members 13' and are arranged in pairs, one on each side of the sheaves 4 and 5, and said members 13' are connected to the main shafts 6 and 7 by the pivoted links 14, certain of which are formed at their ends in bearings in which the shafts 6 and 7 operate. The guide or steadyng rollers guide the line 2 in passing between the sheaves 4 and 5 and prevent the line from passing therebetween at an angle. 15

A flexible shaft 15 is mounted to rotate with and extends from one end of the shaft 6 and said shaft connects at its opposite end 25 with one end of a shaft 16 rotatably mounted in a suitable housing 16' and supported by bearings 17. The shaft 16 carries a suitable pinion 18 which intermeshes with a suitable gear 19 carried by a shaft 19' rotatably mounted in bearings 19'. The shaft 19' carries a worm gear 19' which intermeshes with a suitable gear 19' formed on the lower peripheral edge of a vertically disposed rotatable drum or cylinder 20 through which 30 extends the opposite ends of a shaft 21 which rotates in suitable bearings 22. The upper end of the shaft 21 extends through the top of the housing and carries an indicator hand 23 which is adapted to cooperate with a dial 24 having graduations thereon indicative of lineal feet, said dial and indicator hand being protected by a suitable transparent covering 25.

The drum or cylinder 20 is provided on its outer surface with a vertically disposed row of studs 26 which are adapted to project through suitable apertures in opposite side edges of a suitably ruled chart 27 adapted to be wrapped about the cylinder or 35 drum. The chart 27 is maintained in position by a suitable vertically disposed bar 28 hinged at its lower end, as at 29, to the lower portion of the cylinder 20, and provided within its length with pins 30 which 40 are adapted to extend into the apertures 32 formed on the face of the cylinder or drum, and which are adapted to be forced through the chart 27 when the bar 28 is forced thereagainst. The free end of the 45 bar 28 is adapted to coöperate with a spring catch 33 carried by the upper end of the cylinder or drum 20 and is retained in locked position against the outer face of the chart thereby. The chart 27 is provided on its upper edge with graduations 27' in-

dicative of lineal feet, and is ruled horizontally and each horizontal line is numbered indicative of the hours of the day, including a period preferably from six in the morning until six at night. Vertical rulings on the chart coöperate with the graduations 27' on the upper portion thereof. 70

A suitable marking device 34 coöperates with the chart 27 and the same is yieldably mounted in a support 35 and is maintained in contact with the shaft by a spring 36. The support 35 is formed with a threaded bore through which extends the threaded shaft 37 rotatably supported at its lower end by a frame 37', and at its upper end in a bearing 38, and the rotation of the shaft causes the marking device to move vertically relatively to the chart and provide indications thereon. A guide 39 secured at its ends extends through the marker support 35 and provides a means for preventing the rotation of the support and for maintaining the marker in coöperation with the chart. A beveled pinion 40 is carried by the lower end of the shaft 37 and coöperates with a gear 41 carried by a shaft 42 rotatably mounted in the frame 37' and said shaft 42 carries on one end an operating handle 43 and coöperates at its other end through the ratchets 44 and 44' retained 80 in engagement by the spring 44' with a shaft 45 associated with the hour hand of a suitable clock or other time controlled mechanism 46. The time controlled mechanism is mounted in the side of the housing 100 16' and the hands and dial thereof are visible through a transparent covering 47. The housing is also provided with a transparent panel 48 through which the chart and marking device are visible. 105

It will be apparent that the operation of the clock mechanism 46 will cause the shaft 37 to rotate and which rotation will draw the marking device downwardly on the chart 27. The passing of the back line 2 between 110 the sheaves 4 and 5 will cause the same to rotate, first in one direction and then in a reverse direction, and this motion will be transmitted by the sheave 4 through the respective connected parts to the cylinder 115 or drum 20 and cause the same to oscillate, and the time controlled marking device coöperating with the chart carried by the oscillating drum or cylinder will provide a record of each movement of the cable, a 120 record will also be maintained as to the length of cable unwound from the winding drum and of the time required for the travel of the cable in either direction.

The period of time that the drum remains 125 idle will also be recorded as the marking device then passes thereover in a straight line. When it is desired to reset the marking device to its uppermost position to coöperate with the chart at the beginning of 130

a working day, it is only necessary to grasp the handle 43 and rotate the same in a counter clockwise direction, which will permit the ratchets 44 and 44' to override each other 5 and cause the support to be elevated to the upper portion of the shaft 37.

A pinion 49 is carried on the shaft 16 and intermeshes with a gear 50 mounted to rotate with a shaft 51 and said gear carries at 10 one side a pivotally mounted spring pressed pawl 52 which coöperates with a ratchet 53 loosely mounted on the shaft 51, and causes the ratchet to rotate in one direction. The ratchet is prevented from rotating in a reverse direction by a retaining spring 54 which is mounted on the base of the cabinet, and which coöperates with the teeth of the ratchet.

An arm 55 is carried by the ratchet 53 and 20 the same on each rotation of the ratchet co-operates with the operating wheel 56 of an odometer 57, of any well known type. The cabinet is divided vertically on the line 58 and the sections are hinged, as at 59, to permit access to the interior of the cabinet when 25 it is desired to change the chart, renew or refill the marking device or reset the marking device or wind the clock.

It will be apparent that a structure has 30 been provided wherein the chart after being used is capable of being readily replaced, one wherein the chart is operated relative to the marking device in accordance to the direction and length of travel of the operating cable. By the improved device a chart is maintained as to the daily operation of the cable and by doubling the registration of the odometer, the total travel of the cable may be obtained.

40 The apparatus is so constructed that the gear relation between the sheave 4 and the drum or cylinder 20 is such that the vertical graduations on the chart carried by the drum or cylinder bear a fixed relation to the 45 circumference of the sheave 4 and the movement of the marking device and the horizontal graduations on the chart bear a fixed relation to the operation of the time piece, which construction insures a correct operation 50 of the apparatus under all conditions and at all times.

Having thus described the invention what is desired to protect by Letters Patent is:—

1. In a device of the class described, a recorder, an operating means therefor capable 55 of movement a variable distance in either of two directions, means for transmitting motion from the operating means to the recorder comprising a pair of sheaves between 60 and in direct contact with which the operating means moves, means for maintaining said sheaves in contact with the operating means, and a driving connection between one of said sheaves and the recorder.

65 2. In combination with an operating

means capable of movement a variable distance in either of two directions, a recorder associated therewith, means for transmitting motion from the operating means to the recorder comprising a rotatably mounted 70 body, means for maintaining said rotatably mounted body in direct frictional contact with the operating means, and a driving connection between the rotatably mounted body and the recorder.

3. In combination with an operating means capable of movement a variable distance in either of two directions, a recorder associated therewith, means for transmitting motion from the operating means to the recorder comprising a pair of rotatably mounted sheaves between which the operating means passes, spring mechanism for maintaining said sheaves in contact with said operating means, a frame for mounting said sheaves, a flexible support for said frame, and a driving connection between one of said sheaves and said recorder.

4. In combination with an operating means capable of movement a variable distance in either of two directions, a recorder associated therewith, means for transmitting movement from the operating means to the recorder comprising a frame, coöperating spring pressed sheaves carried by 90 said frame and between which the operating means passes in direct frictional contact, and a driving connection between each of said sheaves and said recorder.

5. In combination with a flexible cable 100 capable of movement a variable distance in either of two directions, a recorder associated therewith, means for transmitting the relative movement of said cable to said recorder comprising a frame, a cable supporting sheave rotatably carried thereby and on which said cable rests, a sheave resting on said cable, means for maintaining said sheaves in frictional contact with said cable, and a driving connection between one of 110 said sheaves and said recorder.

6. In combination with an operating means capable of movement a variable distance in either of two directions, a recorder associated therewith, means for transmitting the relative movement of said operating means to said recorder comprising a frame, a rotatably mounted body carried thereby and with which said operating means frictionally contacts, means carried 115 by the frame for guiding said operating means over said rotatably mounted body, and a driving connection between said rotatably mounted body and said recorder.

7. In combination with an operating 120 means capable of movement a variable distance in either of two directions, a recorder associated therewith, means for transmitting the relative movement of said operating means to said recorder comprising a 125

130

frame, coöperating sheaves carried thereby between and in direct contact with which the operating means moves, one of said sheaves being movable in said frame relatively to the other, means for forcing said movable sheave toward its coöperating sheave, spaced guide rollers supported at one side of the frame with their coöperating surfaces in line with the coöperating

surfaces of said sheaves and between which ¹⁰ the operating means moves, and a driving connection between the movable sheave and the recorder.

In testimony whereof we have signed our names to this specification.

CARL L. KOSTER.
FREDERICK J. DAVIS.
JULIUS J. KROHN.
